BARREL RACK

Lewis O. Porter, Ovid, Colo.

Application October 22, 1936, Serial No. 107,077

5 Claims. (Cl. 248—129)

This invention relates to a barrel rack and aims to provide a novel means to aid in handling large and heavy barrels in particular, for dispensing liquids from the same and for normally enabling the barrel to rest in vertical position so as to avoid leakage about the faucet.

The invention further aims to provide a novel structure wherein roller means are attachable to the barrel and adapted to travel on the rack, as well as facilitating tilting of the barrel.

The more specific objects and advantages will become apparent from a consideration of the description following taken in connection with accompanying drawing illustrating an operative embodiment.

In said drawing:—

Figure 1 is a view in side elevation showing my improvements operatively applied to a barrel;

Figure 2 is a vertical sectional view taken on the line 2—2 of Figure 1, and

Figure 3 is a detail sectional view taken on the line 3—3 of Figure 1.

Referring specifically to the drawing wherein like reference characters designate like or similar parts, a barrel rack or support is shown at A, preferably metallic and of skeleton form made of angle iron although any suitable material may be employed. Such rack has two legs at 10 at one end of the device and at the other end has an arch shape member 11, whose lower ends 12 constitute two additional legs. Extending longitudinally from the legs 10 to the arch 11 are angle or channel track members 13, and suitable braces 14 are bolted as shown to the legs 10 and 12 and track members 13.

A supporting block 15 is disposed within the vertical plane of the arch 11 so that a barrel may rest thereon and it is supported by a cross member 16, secured to the legs 12.

A metallic barrel is shown by way of example at 17 and to adapt it for cooperation with the rack A, rollers 18 are provided thereon, grooved at their periphery as at 19, and adapted to travel along flanges 20 of the members 13. Such rollers 45 may be secured to the barrel in various ways. For example, two arcuate clamp sections 21 and 22, removably surround the barrel, the latter having screw threaded terminals or shanks 23 which are passed through openings 24 in lateral 50 terminals or portions 25 of the section 21. Below the portions 25, nuts 26 are screw threaded on the shanks 23 so as to tightly secure the clamp sections 21 and 22 removably to the barrel. Outwardly beyond the shanks 23, the portions 25 are 55 round as at 27 affording journals for directly

mounting the rollers 18. Cotters may be employed at 28, to prevent displacement of the rollers.

Presuming use of the device, with the barrel and rack disposed relatively close together, the clamp sections 21 and 22 are applied to the barrel and the dispensing faucet or spigot 29 is applied to the barrel. With the aid usually of two men, the barrel is positioned with the rollers 18 engaged with the flanges 20.

Thereupon the barrel may be moved bodily longitudinally of the rack so as to dispose it in horizontal position with one end entered between the arch 11 and supporting block 15. Following a dispensing operation, the barrel may be arranged on its base or lower end so as to prevent leakage about the faucet 29.

Various changes may be resorted to provided they fall within the spirit and scope of the invention.

I claim as my invention:—

1. A device of the class described comprising a rack having an arch member whose terminals constitute legs, track members extending from the arch member, legs secured to the free ends of said track members, supporting means coacting with the arch member adjacent the base of the latter, and said track members being engageable by means on a barrel adapted to enter between the arch member and said supporting means.

2. A device of the class described comprising a rack having an arch member whose terminals constitute legs, track members extending from the arch member, legs secured to the free ends of said track members, supporting means coacting with the arch member adjacent the base of the latter, and said track members being engageable by means on a barrel adapted to enter between the arch member and said supporting means, and brace means connected to the said legs, the legs of the arch member and said track members.

3. A device of the class described, in combination with a barrel, the device comprising a rack having an arch member whose terminals constitute legs, track members extending from the arch member and having upstanding flanges, supporting means coacting with the arch member adjacent the base of the latter, said barrel being adapted to enter between the arch member and said supporting means, rollers on said barrel having peripheral engagement with said track members, legs at the ends of the track members opposite to the arch member, and brace means

connected to the said legs, the legs of the arch member and said track members.

4. A device of the class described, in combination with a barrel, the device comprising a rack having an arch member whose terminals constitute legs, track members extending from the arch member, supporting means coacting with the arch member adjacent the base of the latter, means on said barrel engageable with said track members, said barrel being adapted to enter between the arch member and said supporting means, legs at the ends of the track members opposite to the arch member, brace means connected to the said legs, the legs of the arch member and said track members, said means on the barrel consisting of clamp sections, one section having screw thread-

ed portions extending through the other section, nuts engaging said screw threaded portions and bearing against said other section, and rollers on said other section directly engageable with the track members.

5. A device attachable to a barrel to facilitate movement thereof comprising clamp sections generally of arcuate form, one of said sections having laterally extending portions provided with openings and with journals, rollers carried by said journals, the other section having screw threaded portions extending through said openings, and nuts on said screw threaded portions below said openings.
